(57) **CLAIM**

The ornamental design for the wall recessed outlet box assembly, as shown and described.

DESCRIPTION

FIG. 1 is a front perspective view of the wall recessed outlet box assembly of the present invention;

FIG. 2 is a front elevation view of the assembly of FIG. 1; FIG. 3 is a right side elevation view of the assembly of FIG. 1;

FIG. 4 is a rear elevation view of the assembly of FIG. 1; FIG. 5 is a left side elevation view of the assembly of FIG. 1;

FIG. 6 is a top plan view of the assembly of FIG. 1;

FIG. 7 is a bottom plan view of the assembly of FIG. 1;

FIG. 8 is a front perspective view of an alternative second embodiment of the wall recessed outlet box assembly of FIG. 1;

FIG. 9 is a front elevation view of the assembly of FIG. 8;

FIG. 10 is a right side elevation view of the assembly of FIG. 8;

FIG. 11 is a rear elevation view of the assembly of FIG. 8; FIG. 12 is a left side elevation view of the assembly of FIG. 8;

FIG. 13 is a top plan view of the assembly of FIG. 8;

FIG. 14 is a bottom plan view of the assembly of FIG. 8;

FIG. 15 is a front perspective view of an alternative third embodiment of the wall recessed outlet box assembly of FIG. 1;

FIG. 16 is a front elevation view of the assembly of FIG. 15;

FIG. 17 is a right side elevation view of the assembly of FIG. 15;

FIG. 18 is a rear elevation view of the assembly of FIG. 15;

FIG. 19 is a left side elevation view of the assembly of FIG. 15;

FIG. 20 is a top plan view of the assembly of FIG. 15; and,

FIG. 21 is a bottom plan view of the assembly of FIG. 15.
